UNITED STATES PATENT OFFICE.

EVEN J. ROHNE, OF MINNEAPOLIS, MINNESOTA.

TIRE VULCANIZER.

Application filed January 8, 1921. Serial No. 435,921.

To all whom it may concern:

Be it known that I, EVEN J. ROHNE, a citizen of the United States, residing at Minneapolis, in the county of Hennepin and 5 State of Minnesota, have invented certain new and useful Improvements in Tire Vulcanizers; and I do hereby declare the following to be a full, clear, and exact description of the invention, such as will enable 10 others skilled in the art to which it appertains to make and use the same.

This invention relates to vulcanizing apparatus, and particularly to such an apparatus constructed and arranged for vulcanizing tires. The vulcanizer of this invention is arranged to be electrically heated and to have the electrical heating members controlled by a thermostat. One of the difficulties heretofore experienced with such vulcanizers has been that of overheating, and it is an object of this invention, therefore, to so arrange the heating circuits in the vulcanizer that a certain safe degree of heat will be continuously supplied and further 25 heat may be supplied by the thermostatically controlled circuits.

It is a further object of the invention to provide a vulcanizer having an enclosing housing constructed of sections which are 30 longitudinally separable.

Other objects and advantages of the invention will become apparent from the following description made in connection with the accompanying drawings in which like 35 reference characters refer to the same parts throughout the several views, and in which,

Fig. 1 is a view of the vulcanizer in side elevation, part thereof being shown in section;

Fig. 2 is a view of the same in end elevation as seen from the right in Fig. 1;

Fig. 3 is a partial radial section taken through one end of the vulcanizer, as shown in Fig. 1; and

Fig. 4 is a diagrammatic view showing the wiring arrangement.

Referring to the drawings, the apparatus is seen to comprise a housing made of two sections 10, which, when assembled, form a 50 U-shaped trough of arcuate shape. These sections 10 are provided with central flanges 12 which are provided with bolt holes by which the device can be secured in position by suitable bolts or screws. End flanges 13 55 are also provided having their lower edges in the same parts as the lower edge of the flange

12. The flanges 13 are also provided with bolt holes and the sections 10 are bolted together by nutted bolts 21, extending therethrough, as shown in Figs. 1 and 2. Vertical bosses 14 are provided at each side of the sections 10 centrally of the flanges 12 and these bosses are lapped at their upper ends to receive bolts not shown, which can be tied together by a cross member passing 65 across the top of the sections. As shown in the sectional part of the housing in Fig. 1, the walls thereof are provided with a channel 15 forming a shoulder at each end of the section and a further channel or groove is 70 provided formed in shoulder 16 at each end of the sections. The vulcanizing plate is shown as 17 and is also of U-shape in transverse cross section and arcuate shape longitudinally, to correspond with the shape of 75 the housing member and this member 17 is placed in the housing and has its end portion contacting with the shoulder 16 and its side portions contacting with the shoulder 18, as shown in Fig. 3. It is thus held 80 securely in position.

The plate 17 is arranged to be heated by electrical heating elements comprising covered conductors which are disposed on the surface thereof in longitudinal folds, as 85 shown in Fig. 4. The outside dotted line in Fig. 4 represents an approximate development of the exterior surface of the member 17 and the conductors 1 to 7 are arranged thereon in longitudinal folds, as also indicated by dotted lines in said figure. There are a total of seven conductors, as indicated by the numerals, and these are connected to the terminals of the thermostat *a*. This thermostat comprises movable members *a*¹, each of which is secured at its central portion to a central contact of the thermostat, and normally has its end portion in engagement with other contacts of the thermostat. 90 When the temperature rises sufficiently the ends of these members will move to the dotted line position shown in Fig. 4 and the engagement with the contacts will thus be broken and the circuit closed by said contacts will be opened. There are three contacts of the thermostat at each side thereof, i. e., the end contacts *a*³ and the central contacts *a*² the former of which represent contacts adapted to be opened and closed, while the center contacts are permanently closed 100 and are connected to the line members 8 and 9. The conductors 3, 4 and 5 have both of 105 110

their ends connected to the central contact α^2 of the thermostat, one of these being connected at one side and the other ends being connected at the other side. The conductors 5 1 and 7 have one of their ends connected to the outside contacts α^3 of the thermostat, as is shown at the left of the thermostat, as seen in Fig. 4, while the other ends of members 1 and 7 are connected to the central 10 contacts of the thermostat, as seen at the right hand side of the same in Fig. 4. The conductors 2 and 6 have one of their ends connected to the central contact of the thermostat, as seen at the left of the same in Fig. 4, while their other ends are connected to the outside terminal of the thermostat, as shown at the right hand side of the same in Fig. 4. By this arrangement, the line members 8 and 9 will be continuously connected 15 to three circuits or sets of conductors. The other four circuits or sets of conductors will not be connected to the line members 8 and 9, except when separated by the opening of the outside contacts shown on the thermostat. The thermostat is placed in an aperture formed in the upper corner of one of the sections 1, as shown in Fig. 1, and is covered and protected by a plate member 20 which is fastened to the section by suitable screws. 20 The line members are shown as emerging from the thermostat and covered by an insulating conduit which passes through an aperture formed in the flanges 13. The line members 8 and 9 will, of course, be connected 25 to some suitable source of electric current controlled by a switch.

In operation, the parts to be vulcanized will be placed in the plate 17 and the controlling switch manipulated to supply current to the line members 8 and 9. The plate 40 17 will thus be heated. If the heat supplied exceeds a certain predetermined amount for which the thermostat has been suitably adjusted, one of the contacts thereof will open 45 and will cut out one of the circuits 1, 2, 6 or 7. The three circuits 3, 4 and 5, which are continuously in operations, are so designed that they will not supply enough heat to overheat the vulcanizer. By the use of these 50 three circuits, therefore, and the four thermostatically controlled circuits, the necessary and desired degree of heat will be readily obtained. The folds or coils of the conductors 1 to 7 are designated, generally, as 55 19, and these, as shown in Figs. 1 and 3, will be conveniently disposed in the groove or channel 15 formed in the sections 10.

It is thus seen that applicant has produced a convenient and simple form of vulcanizer and one in which the supply and degree of heat can be accurately and nicely regulated. The vulcanizer can be easily made and quickly and conveniently assembled, and when assembled, is of compact 60 form and of sufficient strength to operate 65

efficiently. It will, of course be understood that various changes may be made in the form and details and arrangement of the apparatus without departing from the scope of applicant's invention, which, generally stated, consists in the matter shown and described and set forth in the appended claims. 70

What is claimed is:

1. A vulcanizing apparatus comprising a plurality of heating circuits permanently 75 connected to the current supplying members and adapted to supply a suitable degree of heat but not capable of overheating the vulcanizer, and a plurality of additional controlled circuits each separately and automatically controlled for supplying additional heat to the vulcanizer and to be cut out when the temperature rises beyond a determined point.

2. A vulcanizer having in combination a 80 vulcanizer plate, a plurality of heating conductors arranged in longitudinal folds thereon, a thermostat carried by said vulcanizer having line contacts and other thermally controlled contacts, certain of the conductors being connected to said line contacts and certain other of the conductors being connected to the thermally controlled contacts. 85

3. A vulcanizer comprising a U-shaped ar- 90 cuate housing formed of two longitudinal sections, a similarly shaped vulcanizing plate disposed therein and abutting shoulders in said housing at its front and side surfaces, and a plurality of heating elements carried 100 by said plate on its exterior surface, said housing having a channel in which said heating elements are disposed. 105

4. A vulcanizer comprising a vulcanizing plate U-shaped in cross section and of ar- 110 cuate shape longitudinally, a plurality of heating conductors disposed on the exterior surface thereof in longitudinal folds, a thermostat carried by said vulcanizer having a pair of line contacts and a pair of opening and closing contacts for each line contact, certain of said conductors being connected to the line contacts of said thermostat at both 115 of their ends and certain other of the conductors having one of their ends connected to the opening and closing contacts, and their other ends connected to the line contacts.

5. A vulcanizer comprising a housing of cross sectional shape and of arcuate shape longitudinally, said housing being divided centrally into longitudinal sections, which sections are provided with flanges through which pass securing bolts for holding said sections together, shoulders formed on the interior of said section and a vulcanizing plate of cross sectional U-shape and of ar- 120 cuate shape longitudinally, having its ends and sides contacting with said shoulders where- 125 by said plate is held firmly in position. 130

6. A heating device comprising a heating member, a plurality of circuits of electrical heating members adapted to supply a suitable degree of heat to said heating member but not capable of overheating the same, and a plurality of additional separate and thermostatically controlled circuits for supplying additional heat to said device.

7. A heating device having in combination 10 a pair of current supplying members, a plurality of electrical heating circuits permanently connected to said members adapted to supply a suitable degree of heat to said device without overheating the same, and a 15 plurality of additional heating circuits thermostatically controlled in their connection to said current supplying members, all of said circuits being uniformly distributed over the whole surface of the heating device.

20 8. A vulcanizing apparatus comprising a pair of current supplying members, a plurality of heating circuits permanently connected to the current supplying members and adapted to supply a suitable degree of heat 25 but not capable of overheating the vulcanizer, and a plurality of additional heating circuits each having a connection to said current supplying members which is thermostatically controlled for supplying additional heat to the vulcanizer, all of said cir-

cuits being uniformly distributed over the whole surface of the vulcanizer, so that no matter what circuits are connected to the current supplying members, the heat will be uniformly distributed.

35

9. A vulcanizing apparatus having in combination an interior vulcanizing plate formed to extend circumferentially of and embrace a tire and an exterior housing embracing said plate, said housing being made in two 40 longitudinally separable sections.

10. A vulcanizing apparatus comprising a plurality of heating circuits permanently connected to the current supplying members and adapted to supply a suitable degree of 45 heat but not capable of overheating the vulcanizer, and a plurality of additional thermostatically controlled circuits for supplying additional heat to the vulcanizer, each one of said circuits being uniformly distributed 50 over the whole surface of the vulcanizer.

11. A heating device comprising a heating member, a circuit comprising a plurality of branches in parallel, said branches being laid upon said heating member in folds and substantially covering the surface of said member.

55

In testimony whereof I affix my signature.
EVEN J. ROHNE.
